[57] **CLAIM**

The ornamental design for a low profile water distillation device, as shown and described.

DESCRIPTION

FIG. 1 is a top perspective view showing the front and right sides of the low profile water distillation device; FIG. 2 is a side sectional view of the ribbing present on the top surface thereof, taken generally along line 2—2 in FIG. 1 on an enlarged scale;

FIG. 3 is a bottom perspective view showing the rear and left sides thereof;

FIG. 4 is a right side elevational view thereof;

FIG. 5 is a left side elevational view thereof;

FIG. 6 is a front elevational view thereof;

FIG. 7 is a rear elevational view thereof;

FIG. 8 is a top elevational view thereof; and,

FIG. 9 is a bottom plan view thereof.

The electrical cord in FIGS. 3-5 and 7 is shown broken away to indicate an indeterminate length.
